DESIGN FOR A YOUTH'S COSTUMER

Jack W. Floyd, Seattle, Wash.

Application November 23, 1945, Serial No. 124,039

Term of patent 7 years

(Cl. D33—8)

To all whom it may concern:

Be it known that I, Jack W. Floyd, a citizen of the United States, residing at Seattle, in the county of King, State of Washington, have invented a new, original, and ornamental Design for Youth's Costumer, of which the following is a specification, reference being had to the accompanying drawing, forming part thereof.

Fig. 1 is a perspective view of a youth's costumer showing my new design.

Fig. 2 is a top plan view of the youth's costumer shown in Fig. 1, and

Fig. 3 is a side view thereof drawn on a smaller scale.

I claim:

The ornamental design for a youth's costumer, as shown.

JACK W. FLOYD.
